ABSTRACT: A circuit for controlling the amplitude of an audio oscillator in an electronic musical instrument in response to the intensity with which a key is depressed. A voltage produced by a coil in response to the movement of a magnet attached to the key charges and output capacitor through a resistor and a diode. A reverse bias of a predetermined level impressed on the diode insures that the time during which a charging voltage is impressed on the capacitor is approximately equal for all levels of voltage produced by the coil.

**CIRCUIT ARRANGEMENT FOR IMITATING THE
TOUCH OF MUSICAL INSTRUMENTS WITH
PERCUSSION**

The invention relates to an electronic musical instrument in which oscillations produced by tone generators are supplied to a member which passes these oscillations only if by touching a key a voltage is impressed on it which is derived from a capacitor which is charged through a rectifying element by a coil in which, when a key is touched, a magnet connected to this key produces a voltage having a value which depends upon the intensity of the touch, which voltage then decreases again to zero.

In such an instrument, it is desirable that the buildup time of the tone for various intensities of touch should be as constant as possible or at least should not exceed a given value with a soft touch, since the character of the instrument is then lost. For example, with a piano, the buildup time never exceeds 10 milliseconds. The term buildup time is to be understood to mean the time in which the tone rises from zero to its maximum amplitude. In the known instrument, this is the time in which the capacitor is charged by a current of a coil in which, when an associated key is touched, an e.m.f. is produced by a magnet connected to this key.

Since the initial and final positions of this magnet are always the same, the flux variation $d\Phi/2$ is constant and the voltage produced is in inverse proportion to the duration τ of the touch and hence in direct proportion to the intensity of the touch. However, it is desirable for this buildup time to be constant or at least to vary to a smaller extent than the duration of the touch.

According to the invention, this is achieved by biasing the rectifying element so that only part of the touching pulse is passed.

With the softest touch, which is the touch producing sound vibrations which are just audible, the bias voltage has a considerably greater influence than with the strongest touch, since the amplitude of the voltage pulses produced by the touch is proportional to the rate at which the magnetic field in the coil is varied, while the bias voltage remains constant. Thus, the part of the voltage pulse produced which is passed by the rectifier has a duration equal to only part of the half period of this voltage pulse, whereas with the strongest touch substantially the whole voltage pulse is passed and hence has a duration of substantially a half period.

With a piano, for example, the ratio between the minimum intensity of touch, i.e. the intensity of touch with which the hammer just reaches the string, and the maximum intensity of touch is in practice approximately 1 : 100. This ratio corresponds to a ratio between the touching times of approximately 10 : 1 and between the amplitudes of the string of approximately 1 : 10 so that the desired ratio between the capacitor voltages is also approximately 1 : 10.

In a preferred embodiment of a musical instrument according to the invention, the bias voltage exceeds half the peak value of the voltage pulse produced with the softest touch. In this case, the ratio between the buildup times is at least 1.5 times and with a triangular voltage pulse, which is usual in practice, even 2 times more favorable than without the application of a bias voltage.

It will be appreciated that this bias voltage can be produced in any known manner, while in certain cases the threshold voltage of the rectifying element may advantageously be used. Alternatively, the rectifying element may be biased by means of the series-combination of a direct voltage source and a resistance which is connected in parallel with the rectifying element, or the direct voltage may be connected in series with the whole charging circuit.

When according to a further embodiment a resistance is connected in the circuit in series with the rectifying element, it is achieved that with the softest touch, the capacitor is charged in a time t_1 which occupies a smaller part of the duration τ_1 of the smallest touching pulse that is the time t_2 of the duration τ_2 of the largest touching pulse with the strongest touch, so that the ratio between the buildup times of the tone

corresponding to t_1 and t_2 becomes even more favorable. The resistance is then chosen to be high with respect to the resistance of the diode.

Thus, it is also achieved that the ratio between the capacitor voltages, which had become unduly large owing to the application of the bias voltage, which results in an unduly large dynamic range, deviates less strongly from the correct value.

In another embodiment of a musical instrument according to the invention, the rectifying element is connected in series with a member the resistance of which increases with increasing current in the starting-current range of the said rectifying element.

This is advantageous in those cases in which the resistance in the circuit is low with respect to the resistance of the diode and in which moreover the rectifying element is operative only in its starting-current range with a soft touch. The step described above ensures that the resistance in the circuit remains more constant so that the phase shift between the charging currents of the capacitor and the pulsatory voltage remains small.

As far as the ratio between the capacitor voltages, which had become unduly large owing to the application of the bias voltage, has not yet or not sufficiently been reduced to the correct value by the step described above, this may be effected in another embodiment of a musical instrument according to the invention by connecting a biased overflow diode in parallel with the coil.

The invention will now be described with reference to the following FIGS. of which:

FIG. 1 shows a circuit arrangement according to the invention;

FIG. 2 shows the variation of the capacitor voltage and of the e.m.f. produced in the coil with different intensities of touch;

FIG. 3 shows a circuit arrangement including a member the resistance of which increases with increasing current;

FIG. 4 shows in a graph the effect of this step;

FIG. 5 shows a circuit arrangement including an overflow diode; and

FIG. 6 shows the voltage variation V of the coil as a function of the intensity of touch.

FIG. 1 illustrates that a magnet 2 coupled with a key 1 varies the magnetic field in the inductance L when the key is depressed. The voltage induced in the inductance L charges a capacitor C through a resistor R and a diode D serving as rectifying element. The diode D is biased with a voltage E supplied by a battery B .

FIG. 2 illustrates the variation of the capacitor voltage as a function of time with two different intensities of touch. The soft touch is associated with the induced voltage E_1 . The half sine E_1 has a duration τ_1 . Without the application of a bias voltage, the capacitor voltage would vary in accordance with the line V_{c1} . It thus appears that the buildup time t_1 slightly exceeds $\frac{1}{2}\tau_1$. It is assumed that the resistance in the circuit is only low with respect to the impedance of the capacitor for this frequency. With a touch which is three times stronger than the softest touch and the associated voltage pulse of which is denoted by E_2 , the voltage across the capacitor becomes V_{c2} . As is apparent from the FIG., the ratio between the times τ_1 and τ_2 is substantially equal to that between the times t_1 and t_2 . When according to the invention the diode D is biased with a voltage E which preferably exceeds half the peak value of E_1 and in the case of the pulse in the form of a half sine shown 0.7 times this value, the duration τ_1 of the voltage pulse E_1 is reduced to τ_3 and the duration τ_2 of the voltage pulse E_2 to τ_4 . In case the voltage pulse is triangular, a bias voltage of 0.5 results in a reduction of the buildup time by 0.5. It will be appreciated that the reduction of these times is larger as the voltage pulse produced is smaller with respect to the bias voltage E . The buildup times t_3 and t_4 of the voltages V_{c1}' and V_{c2}' across the capacitor also decrease, but t_3 to a larger extent than t_4 , so that the ratio between the buildup times, which without the application of a bias voltage was approximately equal to 3

70

is now only 1.5 or smaller. However, due to this step, the ratio between V_{c1}' and V_{c2}' has become larger than 3, which may be undesirable. This disadvantage can be mitigated by connecting a resistor in series with the rectifying element. At higher frequencies and hence with stronger touches, the phase shift between the capacitor voltage and the voltage pulse induced in the coil will then increase, while with strong touches the capacitor voltage V_c will be low with respect to the voltages induced, so that the ratios between these voltages more closely approximate the ratios between the intensities of touch. Moreover, with a stronger touch, the buildup time t_6 of the new capacitor voltage V_{c2}'' thus exceeds t_4 , while the buildup time t_6 of the capacitor voltage V_{c1}'' associated with the soft touch hardly varies with a suitable proportioning of the resistor R and the capacitor C, so that the ratio between the buildup times t_5 and t_6 is even further reduced.

If the peak value of the voltage E_1 induced with the softest touch exceeds the bias voltage E by such a small amount that the diode D is operative only in its starting-current range and if the resistance of the diode is not small with respect to the resistor R, the resistance of the diode varies considerably with a strong and a soft touch; this resistance is a maximum with a soft touch so that the favorable effect of the resistor R is lost again, as is shown in FIG. 4 by the dot-and-dash-line. This effect is compensated for by connecting in series with the diode a member X (cf. FIG. 3) the resistance of which increases with increasing current in the starting-current range of the diode D so that the overall resistance of the circuit varies less strongly. Such a member may comprise a resistor having a positive temperature coefficient, a tunnel diode of which the part having a negative resistance is used, a diode the current of which remains constant in a wide voltage range, and so on. The result is shown by the dotted line in FIG. 4.

For the sake of clarity, FIGS. 2 and 4 show only the case in which the intensity of touch varies only by a factor 3; but it will be appreciated that what has been said as to a touch thrice stronger than the softest touch applies to an even greater extent to a touch intensity ratio of 1 : 10.

The intensity of touch is here always correlated to the rate at which the magnet is pushed into the coil; the amplitude of the voltage pulse is then directly proportional thereto.

As is apparent from FIGS. 2 and 4, the output voltage ratio exceeds 1 : 3.

This may be compensated for by providing an overflow diode biased with the voltage E_1 (cf. FIG. 5). The effect of this diode is shown in FIG. 6, in which the voltage V is plotted on the ordinate and the intensity of touch β on the abscissa. V_s indicates the variation of the voltage across the coil. This varia-

tion is linear. Due to the application of the bias voltage E, the capacitor voltage is reduced by this value at any intensity of touch so that at a ratio between the intensities of touch of, for example, 1 : 3, the ratio between the capacitor voltages has now become 1 : 7, as appears from the variation to the capacitor voltage V_{ci} . The biased overflow diode D_2 , the resistance of which decreases with increasing voltage, ensures that this ratio and hence the dynamic range is brought back to its correct value, as shown by the curve of V_{ci} .

10 The bias voltage of the charging diode D is denoted by E_1 and the bias voltage of the overflow diode by E_2 .

Like in the known instrument, the capacitor voltage is supplied to a control member which passes the oscillations only when the capacitor is in the charged state.

15 The capacitor may also comprise a series-combination of two capacitors and a resistor may be connected in parallel with one of them. Moreover, the capacitor may be connected in parallel with a discharge circuit which ensures that the tone will decay correctly.

20 I claim:

1. A control circuit providing an oscillator in an electronic musical instrument with an output voltage having an amplitude corresponding to the velocity with which movably mounted key is depressed, comprising a magnet, a coil, means for providing relative motion between said coil and said magnet in response to movement of said key, whereby a voltage is induced in said coil corresponding to the velocity of said key, a capacitor, a diode, means for connecting said capacitor and said diode in series, circuit means for connecting said series connected diode and capacitor across said coil, whereby said capacitor is charged in response to the voltage across said coil, and means for biasing the diode with a voltage less than the lowest peak voltage produced in the coil as a result of the softest touch on the key.

35 2. An electronic musical instrument as claimed in claim 1, wherein the bias voltage exceeds half the peak value of the voltage pulse produced with the softest touch.

3. An electronic musical instrument as claimed in claim 1 further comprising a resistor connected in series with the rectifying element.

40 4. An electronic musical instrument as claimed in claim 1, further comprising a member connected in series with the rectifying element, wherein the member has an increasing resistance in response to increasing current in the starting-current range of the rectifying element.

45 5. An electronic musical instrument as claimed in claim 4 further comprising a biased overflow diode connected in parallel with the coil.
